FIRE EXTINGUISHER

Charles R. D'Olive, Dayton, Ohio, assignor to The Fyr-Fyter Company, Dayton, Ohio, a corporation of Ohio

Application June 28, 1929. Serial No. 374,505

5 Claims. (Cl. 169—2)

This invention relates to fire extinguishers.

One of the principal objects of the invention is the provision of a fire extinguisher which is economical to manufacture, is simple in construction and operation, and is highly effective in its action.

Another object of the invention is to provide an extinguisher which may be located adjacent a potential source of fire and may be operated from a remote position, thereby providing a satisfactory extinguisher for a vehicle, such as an airplane.

Other objects and advantages of the invention will be apparent from the following description, the accompanying drawing and the appended claims.

In the drawing, in which like characters of reference designate like parts throughout the several views thereof:

Fig. 1 is a bottom plan view of a fire extinguisher constructed in accordance with this invention;

Fig. 2 is a vertical section taken on the plane of the line 2—2 of Fig. 1;

Fig. 3 is a partial vertical section taken on the plane of the line 3—3 of Fig. 2;

Fig. 4 is a view similar to Fig. 3 showing a modification;

Fig. 5 is a section through an airplane engine housing showing the extinguisher of this invention mounted therein; and

Fig. 6 is a diagrammatic showing of a tri-motor airplane in which are mounted extinguishers embodying the present invention.

Referring more particularly to the drawing, in which is illustrated a preferred embodiment of the invention, the numeral 10 designates a fire extinguisher comprising a cylindrical sheet metal casing adapted to hold a charge of fire extinguishing fluid. The casing 11 is closed at one end by a wall 12 which may be formed integral with the casing, and at the other end by a cast metal end wall 13 soldered to the casing. The end wall 13 is provided with an inwardly extending threaded portion 14 within which is screwed a filling plug 15 having a sealing gasket 16.

The cylindrical casing is preferably provided with an indented portion 17 extending longitudinally thereof. Within this indented portion is formed a slot or slots 18 which serve as discharge ports for the release of the contents of the container. In order to aid the discharge, vent tubes are provided. Each vent tube has an outwardly flared end portion 21 which is soldered or otherwise attached to the container wall with-

in the indented portion. The vent tubes extend upwardly and open within the container adjacent the wall thereof opposite the indented portion. Preferably a plurality of vent tubes 20 are provided, as shown in Fig. 2, where one is positioned adjacent each end wall so that if the extinguisher is put into operation while in tilted position at least one of the vent tube openings will be above the level of the fluid within the container and will provide a path for air to enter the container and displace the fluid contents to aid in the rapid discharge of the contents. A sealing member 22, which may be a thin metallic strip of shim stock, is attached to the surface of the container within the indented portion by running soft solder or like material indicated at 23 into the joint between the edges of the sealing member and the surface of the indented portion. This serves to seal the slot and vent tube openings so as to provide an airtight closure for the container. One end of the sealing member is provided with a loop 30 or other attaching means to which an operating cable such as the pull cord 31 is secured so that upon actuation of the pull cord the soft solder joint between the sealing member and the container wall will be broken and the sealing member will be torn away from the container, thus exposing the discharge ports 18 and the vent tubes 20 to permit discharge of the extinguishing liquid from the container in the form of a curtain or sheet spray.

Fig. 4 shows a modified construction in which the container wall 11 is slotted and the adjacent edges of the slot are bent inwardly as at 25 to provide a V-shape trough within which is laid a wire 26. Solder indicated at 27 is run into the space between the wire and the bent-in surfaces of the container wall to provide a sealed joint over the slotted opening 28.

In Fig. 5 an extinguisher 10 constructed in the manner above described is shown mounted within the housing 35 of the engine compartment of an airplane. The engine 36, to the crank shaft of which is attached a propeller 37, has intake pipes 38 communicating with a manifold 39 which in turn is connected to the carburetor 40. The extinguisher 10 is held in place by brackets 41, one of which is shown, and is mounted with the slotted opening 18 and the sealing strip on the bottom side of the extinguisher. A pull cord 31 is attached to the sealing member of the extinguisher and extends to some position in the airplane convenient to the occupants, so that in case of a fire a pull on the cord 31 will tear the sealing strip from the extinguisher, thus permit-

ting the contents to be discharged by gravity and to be carried over the carburetor and its associated parts.

In Fig. 6 extinguishers are shown applied to a tri-motored airplane. An extinguisher 10 is positioned in each of the engine compartments and to each extinguisher is attached a pull cord 31. The pull cords 31 terminate in control handles 42 which are within easy reach of the pilot who is stationed within the cock pit 43. If a fire should start in any one of the engine compartments the pilot, by pulling the respective control cord extending to the particular compartment in which the fire originated, can discharge the contents of that particular extinguisher without actuation of the others. Upon removing the sealing strip the extinguishing fluid will fall by gravity and will be sprayed by the slip stream or air currents created by the propeller through the engine compartment.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. A fire extinguisher comprising a container adapted to hold a fire extinguishing fluid, a discharge port for said container, a vent for said container, means releasably fastened to said container over said discharge port and said vent for sealing said discharge port and said vent, and manually operable means for removing said sealing means from the container so as to expose said discharge port and said vent with resultant discharge of said fire extinguishing fluid.

2. A fire extinguisher comprising an elongate container adapted to hold a fire extinguishing fluid, said container having a discharge port in the side wall thereof, the container being adapted to be supported in position with said port adjacent the lower side thereof, a vent tube extending within the container from said lower side wall of the container adjacent the discharge port and opening within the upper portion of the container, means fastened to said container over

said port and said vent tube for sealing said port and said vent tube, and means for removing said sealing means from the container so as to expose the said port and vent tube with resultant discharge of said fire extinguishing fluid.

3. A fire extinguisher comprising a container, adapted to hold a fire extinguishing fluid, said container having an indented portion in the side wall thereof extending longitudinally of the container, said container having a discharge port in said indented portion, a vent tube opening within the extinguisher and fastened to the interior of the indented portion of said container, sealing means attached to the container within the indented portion providing a closure for said discharge port and vent tube, and means for manually stripping said sealing means from said container to expose said discharge port and vent tube.

4. A fire extinguisher of the character described comprising an elongate container adapted to hold a fire extinguishing fluid, said container having an elongate slot in the side wall thereof extending longitudinally of said container, a plurality of vent tubes extending from said slot in the side wall of the container and opening within the container adjacent the opposite wall thereof, there being a vent tube adjacent each end of the extinguisher, a sealing member providing a closure for said slot and vent tubes, means such as soft solder for releasably fastening said sealing member to said extinguisher, and means for effecting stripping of said sealing member from said extinguisher.

5. A fire extinguisher comprising a container adapted to hold a fire extinguishing fluid and having a gravity discharge port for the discharge of said extinguishing fluid from the extinguisher, a sealing member for the discharge port, a vent for the container, means such as soft solder for releasably fastening the sealing member to the container over the discharge port and vent, and manually operable means for removing said sealing member from the container so as to expose said port and vent with resultant discharge of said fire extinguishing fluid.
